United States Patent Office

Des. 182,873
Patented May 27, 1958

182,873

PORTABLE WASHING MACHINE

Melvin H. Boldt, Glenview, Ill.

Application December 24, 1956, Serial No. 44,320

Term of patent 14 years

(Cl. D49—1)

I claim:

The ornamental design for a portable washing machine, as shown.
